BUTTON SPINNING MACHINE

Benjamin Sklerov, Harry Sklerov, and Joseph Solinsky, New York, N. Y., assignors to Sam Steinglass, New York, N. Y.

Application June 15, 1944, Serial No. 540,416

15 Claims. (Cl. 91—60)

This invention relates to button spinning machine.

In painting or decorating buttons it is often necessary to spin the button so that an operator can apply a paint brush to the button as it spins, whereby a circular line or band of paint is applied to the button. Heretofore these buttons were mounted on a rotary member which was spun manually to give the operator an opportunity to apply paint. An operator could therefore only paint one button at a time. It is hence an object of the present invention to provide a button spinning machine provided with two sets of spindles, both motor operated, each spindle being adapted to receive a button to be decorated, the arrangement being such that while one set of spindles are being rotated so that the operator can apply paint thereto, rotation of the other set of spindles is stopped, the painted buttons flipped off or removed and a fresh set of buttons mounted, so that as soon as the buttons on the first set of spindles are decorated, that set of spindles can be stopped and rotation of the spindles with the unpainted buttons can be started so that an operator can apply paint thereto. The machine can thus be worked with two operators, one to apply paint or to decorate the spinning buttons and the other operator to remove painted or decorated buttons and mount fresh buttons on the spindle. With such an arrangement, a very high rate of production can be obtained in comparison with the former method of manually spinning a spindle and decorating the buttons one at a time.

Another object of this invention is to provide in a machine of the character described, a rotary member and a spindle removably mounted thereon for rotation therewith, whereby spindles of various sizes can be mounted thereon, and each spindle being provided with a recess to receive the button to be painted or decorated and with notches communicating with the recess so that a finger of the operator can be moved through the notch to flip a painted button out of the spindle.

Still another object of this invention is to provide a machine of the character described comprising two sets of spindles located on a table and having provision for an operator to sit on one side of a table and between the sets of spindles, so that the operator can paint or decorate buttons on either set of spindles, and so that another operator can sit on the opposite side of the table and between the two sets of spindles so as to be in a position for removing painted but-

tons and loading unpainted buttons on either set of spindles, each set of spindles furthermore being provided with separate electric motor power drive and clutches under control of one of the operators to connect the motors with the spindles.

Yet a further object of this invention is to provide a compact and sturdy machine of the character described which shall be relatively inexpensive to manufacture, easy to manipulate, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a top plan view of a machine embodying the invention;

Fig. 2 is a front elevational view thereof;

Fig. 3 is a cross-sectional view taken on line 3—3 of Fig. 2;

Fig. 4 is a cross-sectional view taken on line 4—4 of Fig. 2; and

Fig. 5 is a top plan view of one of the spindles.

Referring now in detail to the drawings, 10 designates a button spinning machine embodying the invention. The same comprises a table 11 having a table top 12 and a frame 13 supporting the table top. The frame 13 comprises a pair of similar vertical, symmetrically disposed end members 14 on which the table top rests. Each of the frame members 14 has a front leg 15, a rear leg 16, and an interconnecting horizontal lower brace 17 extending from front to rear. Supported by the braces 17 is a transverse, horizontal foot board 18. Attached to the front of the frame 13 is a front wall 20 having a central cut out 21 to receive the legs of an operator sitting in front of the table and facing the same.

Thus the front wall 20 has side portions 22 and a top connecting portion 23. The table may also be provided if desired, with end walls 24 and a rear wall 25. The rear wall 25 is also provided with a central opening similar to opening 21 in the front wall, to receive the legs of an operator sitting at the back of the table and facing the table.

As shown in the drawings, the foot board 18 is closer to the front wall 20 than to the rear wall,

so that it can be reached by the feet of the front operator for the purpose hereinafter appearing.

Table top 12 is formed with a centrally located longitudinal recess 12a in which is inserted a flat elongated bar or plate 30 parallel to the front and rear edges of the table top. Plate 30 is formed with two spaced sets of holes 31, and the table top 12 is formed with two spaced sets of holes 32 registering with the holes 31. In each of the registering holes 31, 32 is an anti-friction bushing 33 such as a bronze bushing.

Mounted within each bushing is an adaptor 34. Each adaptor 34 has a central socket 35 open at its upper end. It is also formed with an annular flange 36 at its upper end contacting the upper end of the bushing 32. At the lower end of each adaptor is a downwardly extending stem 37. As shown in the drawings for the purpose of illustration, there are six adaptors 34 in each set. The first and last adaptors of each set have short stems on which are mounted pulleys 39 and 40 respectively. On the second and fifth adaptors of each set are somewhat longer stems to which are fixed upper pulleys 41 and 42 and lower pulleys 43 and 44. On the fourth adaptor of each set is a stem similar to stems on the second and fifth adaptors and fixed thereto is an upper pulley 45 and a lower pulley 46. On the third adaptor of each set is a still longer stem on which is mounted an upper pulley 47, a lower pulley 48 aligned with the pulleys 43, 46 and 44, and a still lower main pulley 49. The pulleys 39 and 41 are connected by a belt 50. The pulleys 41, 45 are interconnected by a belt 51. The pulleys 42, 40 are interconnected by a belt 52. Pulleys 43, 48 are interconnected by a belt 54. Pulleys 46, 44 are interconnected by a belt 55. It will now be understood that upon rotating each pulley 49, all of the adaptors in the same set will be rotated.

On each adaptor is mounted a spindle 60. Each spindle 60 has a cylindrical head 61 and a stem 62. The stem fits into socket 35 of the adaptor. The upper end of each adaptor is formed with an offset hole 65 to receive a pin 66 on the underside of the head of the spindle. Thus each spindle is removable from its adaptor by lifting, but when mounted thereon with its pin 66 fitted into the hole 65 the spindle will rotate with the adaptor. Each spindle is formed at the upper end thereof with an annular central shallow recess 70 and with a smaller recess 71 below the recess 70. The button to be painted or decorated may be placed within the recess 70. The head 61 of each spindle may be provided with a plurality of equiangularly spaced notches 75 communicating with edge portions of recess 70 to permit the thumb on the finger of the operator to be inserted into one of the notches for engaging the underside of the button to flip it out of the recess 70.

Means is provided for selectively rotating each set of spindles. To this end there is attached to the underside of the table top 12 at each end thereof, a frame or hanger 16. Each frame 16 is provided with a pair of parallel downwardly extending arms 11 carrying aligned bearings 18.

Rotatably and slidably mounted in each pair of bearings 18 is a horizontal shaft 79. On the rear end of shaft 79 is a friction disc clutch 80. Mounted on said shaft is a grooved clutch sleeve or collar 81. Clutch disc 80 has a hub 83 on which is mounted a pulley 84. Attached to the underside of each frame 16 is an electric motor 86, on the armature of which is mounted a fric-

tion clutch disc 87 adapted to be contacted by the clutch disc 80.

Looking at Fig. 3 it will be seen that rotation of shaft 79 will be started upon shifting said shaft to the left a sufficient distance to engage clutch disc 80 with clutch disc 87.

Means is provided to connect shaft 79 for rotation with pulley 49. To this end there is attached to the underside of table top 12 a hanger 90 on which is mounted for rotation a horizontal shaft 91. On shaft 91 are a pair of parallel pulleys 92, 93. Interconnecting pulley 49 with pulley 84 is a belt 94. The belt has one run passing over pulley 93 and one run over pulley 92. The pulleys 91, 92 are idlers. When one of the motors is operated and the clutch 80, 81 is interconnected; the pulley 84 will be rotated and therefore belt 94 will rotate the pulley 49 connected thereby. Each motor may be provided with a separate "on" and "off" switch 100 for individually energizing the motors.

Means is provided for selectively shifting the shafts 79 so that the operator sitting at the front of the table can cause spinning of either set of spindles. To this end one of the arms 11 of frame 16 has a downwardly extending projection 101 to which is pivoted as on pivot 103 a bell crank 102. Bell crank 102 has a forked arm 104 engaging the grooved clutch collar or sleeve 81. Said bell crank furthermore has a second arm 105 extending rearwardly from the pivot point.

Mounted on foot board 18 are a pair of spaced foot pedals 107. The pedals may be depressed by the left or right foot of the front operator, respectively. Connected to each foot pedal and extending outwardly therefrom is a fixed arm 108. Connected to the outer end of bell crank arm 105 is a connecting rod 110. The rod 110 passes through a slot groove or opening 111 at the outer end of arm 108. At the lower end of rod 110 is a stop 112. Interposed between the stop 112 and arm 108 is a coil compression spring 113.

It will now be understood that when the left pedal 107 is depressed the connecting rod connected thereto, will operate the bell crank 102 on that side of the machine for starting the spinning operation for the left set of spindles. When the foot pedal is released the clutch is released and the spindles of that set stop spinning. The set of spindles on the right side of the machine may be started by depressing the foot pedal 107 on the right side, and this set of spindles stops rotating when the foot pedal on the right is released.

In operating the machine one operator sits in front of the table or machine and one in back. One set of spindles is first loaded with buttons. The foot pedal is depressed to spin the spindles and they are painted by the front operator. While they are being painted, the other set of spindles are loaded by the rear operator. When the first set of buttons have been painted, rotation of the spindles is stopped by releasing one foot pedal, and the other set of spindles are spun by depressing the other foot pedal so that the other set can be painted. While the second set of buttons are being painted the rear operator flips the buttons out of the spindles of the first set and loads new buttons thereon.

The spindles 60 are removable by merely lifting them up out of the adaptors and other spindles having different size recesses 70 to accommodate different size buttons, may be inserted.

Adjustable means is provided to limit move-

ment of each shaft 79. To this end there is integrally formed with portion 101 of each frame 76, an upwardly extending arm 120 formed with a screw threaded opening 121 aligned with shaft 79. Screwed within said opening is an adjustable screw 122 adapted to limit movement of shaft 79 in one direction. Front wall 20 is provided with an opening 20a to give access to screw 122.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:

1. A button spinning machine comprising a set of spaced adaptors, spindles removably mounted on the adaptors, means to simultaneously rotate said adaptors, including an electric motor, an adaptor drive, clutch means to connect the motor to the drive, and means under the control of an operator to actuate said clutch means.

2. A button spinning machine comprising a table having a table top, two spaced sets of adaptors rotatably mounted on the table top, said sets being in alignment and the adaptors in each set being in a row, said sets being located on opposite sides of the middle of the table top, means to interconnect the adaptors of each set for simultaneous rotation, an electric motor for each set, a drive for each set, and clutch means to connect each motor to its drive.

3. A button spinning machine comprising a table having a table top, two spaced sets of adaptors rotatably mounted on the table top, said sets being in alignment and the adaptors in each set being in a row, said sets being located on opposite sides of the middle of the table top, means to interconnect the adaptors of each set for simultaneous rotation, an electric motor for each set, a drive for each set, clutch means to connect each motor to its drive, and foot pedal means to control each clutch, located on opposite sides of the middle of the table so as to be under the control of one operator.

4. In a button spinning machine, a table, an adaptor rotatably mounted thereon, a spindle mounted on the adaptor, means to connect the spindle to the adaptor for rotation therewith, said spindle having a recess on the upper surface to receive a button.

5. In a button spinning machine, a table, an adaptor rotatably mounted thereon, a spindle mounted on the adaptor, means to connect the spindle to the adaptor for rotation therewith, said spindle having a recess on the upper surface to receive a button, and said spindle being provided with a plurality of notches communicating with said recess to permit the button to be flipped out.

6. In a button spinning machine, a row of vertical adaptors, means to simultaneously rotate said adaptors, each adaptor being provided with a socket open at the top, a spindle mounted on each adaptor, each spindle having a stem received in the socket and a head resting on the upper end of the adaptor, said spindle being provided with a recess to receive a button.

7. In a button spinning machine, a row of vertical adaptors, means to simultaneously rotate said adaptors, each adaptor being provided with a socket open at the top, a spindle mounted on each adaptor, each spindle having a stem received in the socket and a head resting on the upper end of the adaptor, said spindle being provided with a recess to receive a button, and pin and socket means on said spindle and adaptor offset from the axis of said spindle and adaptor, whereby to connect the spindle to the adaptor for rotation therewith.

8. In a button spinning machine, a row of vertical adaptors, means to simultaneously rotate said adaptors, each adaptor being provided with a socket open at the top, a spindle mounted on each adaptor, each spindle having a stem received in the socket and a head resting on the upper end of the adaptor, said spindle being provided with a recess to receive a button, and pin and socket means on said spindle and adaptor offset from the axis of said spindle and adaptor, whereby to connect the spindle to the adaptor for rotation therewith.

15 9. In a button spinning machine, a row of vertical adaptors, means to simultaneously rotate said adaptors, each adaptor being provided with a socket open at the top, a spindle mounted on each adaptor, each spindle having a stem received in the socket and a head resting on the upper end of the adaptor, said spindle being provided with a recess to receive a button, and pin and socket means on said spindle and adaptor offset from the axis of said spindle and adaptor, whereby to connect the spindle to the adaptor for rotation therewith, the head of the spindle being formed with a plurality of notches communicating with the button recess.

20 10. A button spinning machine comprising a table having a table top formed with a row of spaced vertical openings, adaptors rotatably mounted in said openings, means to interconnect said adaptors for simultaneous rotation, and a spindle removably mounted on each adaptor and connected thereto for rotation therewith.

25 11. A button spinning machine comprising a table having a table top formed with a row of spaced vertical openings, adaptors rotatably mounted in said openings, means to interconnect said adaptors for simultaneous rotation, and a spindle removably mounted on each adaptor and connected thereto for rotation therewith, each spindle having a recess at its upper end to receive a button.

30 12. A button spinning machine comprising a table having a table top formed with a row of spaced vertical openings, adaptors rotatably mounted in said openings, means to interconnect said adaptors for simultaneous rotation, a spindle removably mounted on each adaptor and connected thereto for rotation therewith, each spindle having a recess at its upper end to receive a button, and each spindle being formed with a plurality of equiangularly spaced notches in the sides thereof communicating with said recess.

35 13. A button spinning machine comprising a table having a table top formed with a row of spaced vertical openings, adaptors rotatably mounted in said openings, means to interconnect said adaptors for simultaneous rotation, a spindle removably mounted on each adaptor and connected thereto for rotation therewith, each spindle having a recess at its upper end to receive a button, each spindle being formed with a plurality of equiangularly spaced notches in the sides thereof communicating with said recess, a pulley on one of said adaptors, a shiftable shaft, a pulley on said shiftable shaft, a belt interconnecting said pulleys, a friction disc on said shiftable shaft, an electric motor, and a friction disc on said motor adapted to be contacted by the first friction disc upon shifting said shaft in one direction.

40 14. A button spinning machine comprising a table having a table top formed with a row of spaced vertical openings, adaptors rotatably mounted in said openings, means to interconnect said adaptors for simultaneous rotation, a spindle removably mounted on each adaptor and connected thereto for rotation therewith, each spindle having a recess at its upper end to receive a button, each spindle being formed with a plurality of equiangularly spaced notches in the sides thereof communicating with said recess, a pulley on one of said adaptors, a shiftable shaft, a pulley on said shiftable shaft, a belt interconnecting said pulleys, a friction disc on said shiftable shaft, an electric motor, and a friction disc on said motor adapted to be contacted by the first friction disc upon shifting said shaft in one direction.

45 15. A button spinning machine comprising a table having a table top formed with a row of spaced vertical openings, adaptors rotatably mounted in said openings, means to interconnect said adaptors for simultaneous rotation, a spindle removably mounted on each adaptor and connected thereto for rotation therewith, each spindle having a recess at its upper end to receive a button, each spindle being formed with a plurality of equiangularly spaced notches in the sides thereof communicating with said recess, a pulley on one of said adaptors, a shiftable shaft, a pulley on said shiftable shaft, a belt interconnecting said pulleys, a friction disc on said shiftable shaft, an electric motor, and a friction disc on said motor adapted to be contacted by the first friction disc upon shifting said shaft in one direction.

said adaptors for simultaneous rotation; a spindle removably mounted on each adaptor and connected thereto for rotation therewith, each spindle having a recess at its upper end to receive a button, each spindle being formed with a plurality of equiangularly spaced notches in the sides thereof communicating with said recess, a pulley on one of said adaptors, a shiftable shaft, a pulley on said shiftable shaft, a belt interconnecting said pulleys, a friction disc on said shiftable shaft, an electric motor, a friction disc on said motor adapted to be contacted by the first friction disc upon shifting said shaft in one direction, and means to shift said shaft.

14. A button spinning machine comprising a table having a table top formed with a row of spaced vertical openings, adaptors rotatably mounted in said openings, means to interconnect said adaptors for simultaneous rotation, a spindle removably mounted on each adaptor and connected thereto for rotation therewith, each spindle having a recess at its upper end to receive a button, each spindle being formed with a plurality of equiangularly spaced notches in the sides thereof communicating with said recess, a 15

pulley on one of said adaptors, a shiftable shaft, a pulley on said shiftable shaft, a belt interconnecting said pulleys, a friction disc on said shiftable shaft, an electric motor, a friction disc on said motor adapted to be contacted by the first friction disc upon shifting said shaft in one direction, means to shift said shaft, and adjustable means to limit movement of the shaft in an opposite direction.

15. A button spinning machine comprising a table having a table top formed with a row of spaced vertical openings, adaptors rotatably mounted in said openings, means to interconnect said adaptors for simultaneous rotation, a spindle removably mounted on each adaptor and connected thereto for rotation therewith, a pulley on one of said adaptors, a shiftable shaft, a pulley on said shiftable shaft, a belt interconnecting said pulleys, a friction disc on said shiftable shaft, an electric motor, and a friction disc on said motor adapted to be contacted by the first friction disc upon shifting said shaft in one direction.
